UNITED STATES PATENT OFFICE.

MAHLON E. LAYNE, OF HOUSTON, TEXAS.

WELL SCREEN.

Application filed April 19, 1923. Serial No. 633,082.

To all whom it may concern:

Be it known that I, MAHLON E. LAYNE, a citizen of the United States, residing at Houston, in the county of Houston and State 5 of Texas, have invented a new and useful Well Screen, of which the following is a specification.

This invention relates to well screens such as are used for screening out sand or other 10 solids from the liquid entering the well casing.

Many types of perforated well screens have heretofore been proposed having various forms of normally open perforations 15 and having different types of projecting lips or tongues extending outwardly over the perforations. It has been found that in instances where the perforations are normally open, that is where the screen is completed in its final form before insertion into 20 a well, the screen cannot be driven into the earth or readily inserted into a well bore without clogging the perforations to such an extent as to render the screen partly, if 25 not entirely, inefficient. Further it has been found that with screens having outwardly projecting lips or other projections such clogging is augmented especially in attempting to drive such a screen into the 30 earth.

It is an object of the present invention to overcome such objectionable features by providing a screen as an article of manufacture and in which the protecting lips or 35 tongues are normally closed over the associated perforations during the driving or inserting of the screen to its position of use and in which the tongues are subsequently forced outwardly to open the perforations; to provide a structure which in 40 its normal condition presents a smooth continuous exterior surface facilitating such driving or insertion of the screen; and to provide a screen comprising an inner perforated pipe and an outer pipe formed of 45 a metal ribbon wound spirally around the inner pipe coil on coil and split longitudinally of the pipe on opposite sides of each 50 perforation to define tongues which are normally closed to present a smooth continuous exterior surface during insertion of the screen and which are adapted to be forced outwardly after the screen is in place.

Another object is to provide a screen 55 which will be exceedingly strong and du-

rable, which may be economically manufactured, and which will efficiently perform the services of which it is designed.

Various other objects and advantages will 60 be more fully apparent from the following description of the accompanying drawings which form a part of this disclosure, and which illustrate a preferred form of embodiment of the invention.

Of the drawings:

Figure 1 is a side elevation, partly in section, of one form of the screen of the present invention.

Fig. 2 is an enlarged detail section showing some of the tongues in closed position.

Fig. 3 is an elevation, similar to Fig. 1, showing another form of the screen, and

Fig. 4 is an enlarged detail section, similar to Fig. 2 of a portion of the screen 75 shown in Fig. 3.

In Figs. 1 and 2, the screen comprises an inner pipe 1 which is provided with a plurality of spirally arranged perforations 2 relatively positioned so as to form longitudinal rows relatively spaced around the pipe, and an outer pipe which is formed of a metal ribbon 3 wound spirally around the inner pipe coil on coil to correspond to the spiral progression of the perforations 2 and preferably with the lower half of the ribbon overlapping the perforations. The ribbon is grooved or scored lengthwise as at 4 and is split inwardly from its lower edge to the groove 4 on opposite sides of 90 each of the perforations 2, as indicated at 5, to define tongues 6 overlying the perforations.

The opposite edges of the ribbon are beveled outwardly and downwardly with 95 the split edge of each convolution overlapping the upper edge of the adjacent convolution, so that when the tongues 6 are bent outwardly the adjacent beveled edges form an upwardly angled throat 7 communicating with the companion perforation (see Fig. 2).

The ribbon 3 is preferably of substantial thickness so as to materially strengthen the inner pipe and also to provide tongues of sufficient thickness to withstand hard usage, and for this reason the groove 4 is particularly advantageous in contributing to an easy bending of the tongues.

In the form of screen shown in Figs. 3 110 and 4, the ribbon 3 is wound upon the inner pipe 1 with the meeting edges of

tudinal rows of relatively spaced perforations in its walls, and an outer pipe formed of a metal ribbon grooved lengthwise and wound spirally around the inner pipe, one edge of the ribbon being slit longitudinally of the pipe to said groove and on opposite sides of each perforation to define tongues adapted to be subsequently bent outwardly to form to 5 openings communicating with the perforations in the inner pipe.

10. An article of manufacture comprising an inner pipe having a plurality of rel-

atively spaced perforations in its wall, and an outer pipe formed of a metal ribbon wound spirally around the pipe coil on coil, both edges of said ribbon being split longitudinally of the pipe on opposite sides of each perforation to define tongues adapted to be subsequently bent outwardly to form 15 openings communicating with the perforations in the inner pipe.

Signed at South Pasadena, Cal., this 12th day of April 1923.
